UNITED STATES PATENT OFFICE.

WILLIAM GARDAM AND JOSEPH GARDAM, OF WILLIAMSBURG, NEW YORK.

IMPROVEMENT IN DRILLING-MACHINES.

Specification forming part of Letters Patent No. 123,886, dated February 20, 1872.

SPECIFICATION.

We, WILLIAM GARDAM and JOSEPH GARDAM, of Williamsburg, county of Kings and State of New York, have invented certain new and useful Improvements in Drilling-Machines, of which the following is a specification:

Our invention relates to an improvement in drilling-machines; and it consists of the addition, to an adjustable belt-tightening device, of a screw-threaded extension to the axle of the tightening-pulley, as will hereinafter be more fully set forth.

Figure 1, in the accompanying drawing, is a side view of our invention, and Fig. 2 is a rear view of the same.

The main frame *a* is provided with a bearing, *a*¹, for the stem of the table *h* to work in, said table being held at any desired height by the set-screw *h*¹. The main frame is also provided with bearings *a*² *a*³ at the upper part, which are in line with the bearing *a*¹. Between the bearings *a*² *a*³ is placed the pulley *d*, which gives motion to the drill-spindle *c*, by means of a longitudinal groove in the spindle *c* and a pin or feather in the pulley *d* working therein, so the spindle *c* is free to move up or down. The drill-spindle *c* is moved to or from the work on the table *h* by the hand-lever *e*, which is pivoted to the cap *e*¹ on the top of the spindle *c*, and to two links, *f* and *f*¹, the other ends of the links being pivoted to the projection *a*⁴ from the main frame *a*, forming the fulcrum of the lever *e*. The spring *e*², fastened to the le-

ver *e* and the main frame *a*, is to raise the drill-spindle *c* from the table *h*. The two pulleys, *g* and *g*¹, are for guiding the belt *h* onto the pulley *d*. They are on the sliding bracket *g*², which may be moved out to tighten the belt when it gets slack, and retained by the thumb-screw *i*. The drawing shows the position of the sliding bracket *g*² when the belt *h* is being guided from a pulley beneath the table, to adjust it so as to run the machine from a pulley above. The sliding bracket is placed in the hole shown by dotted lines at *a*⁵. The guide-pulleys would then be in the position shown by the dotted lines *h*. The spindle *z*, on which the guide-pulleys *g* and *g*¹ are placed, is extended or lengthened, as shown at *z*¹, for the purpose of putting on polishing brushes, wheels, &c. The pulley *g*¹ is fast to the spindle *z*, and consequently gives motion to it. The other pulley *g* turns loose on it. The spindle *z* may be extended or lengthened on both sides of the machine.

We claim as our invention—

The addition to an adjustable belt-tightening device of the screw-threaded extension to the axle of the tightening-pulley, as and for the purpose set forth.

WILLIAM GARDAM.
JOSEPH GARDAM.
